SEAL FOR KEGS

Thomas N. Bourke, Grosse Pointe, Mich.

Application May 24, 1941, Serial No. 394,965

8 Claims. (Cl. 217—99)

This invention relates to a seal for kegs, and particularly for kegs used for beer.

It has been the practice to equip the head of a keg with a plug or cork which is knocked out of position and into the keg when the draft tube is secured to the keg. The draft tube itself is usually employed to knock the cork into the keg and then the draft tube lies in the aperture. One of the major difficulties with this arrangement is that after the keg is empty the aperture is open and dirt and other extraneous matter, flies or vermin are attracted and get into the opening. As a result, when the kegs are returned to the brewery for refilling they have to be carefully inspected and cleaned, and in many instances the pitch lining has to be burned off and the keg re-pitched, or in other words, relined with a new pitch coating. Moreover, a cork is wasted and destroyed for each filling.

The object of this invention is to provide a keg seal to overcome these objections. The construction is one which will remain sealed against the internal pressure, and yet one through which the draft tube can be easily inserted. This structure is of a permanent nature and it will last for a long period of time, and no parts are used or consumed with each filling. Moreover, when the draft tube is removed after the keg is empty, the seal structure automatically closes and keeps out all extraneous matter and things.

The structure also provides an auxiliary closure means, both exterior of the keg and interior of the keg, so that exterior extraneous matter is prevented from access to the parts which actually effect the seal and so that these same parts are protected from the interior. Thus when it is necessary to remove the pitch lining from the interior of the keg and to apply a new lining, the seal structure may remain in position and the sealing parts are protected from the flame in the de-pitching operation and from the newly applied pitch lining.

A construction for carrying out the invention is disclosed in the accompanying drawings. In the drawings

Fig. 1 is an elevational view of a keg illustrating the draft tube applied thereto.

Fig. 2 is an enlarged cross sectional view taken through the head of the keg and showing the seal structure.

Fig. 3 is a cross sectional view taken substantially on line 3—3 of Fig. 2.

Fig. 4 is a view of the sealing element.

Fig. 5 is a cross sectional view similar to Fig. 2 showing the draft tube applied to the keg.

Fig. 6 is a sectional view taken substantially on line 6—6 of Fig. 5.

Fig. 7 is a sectional view taken substantially on line 7—7 of Fig. 5 showing certain parts of the draft or tap mechanism.

Fig. 8 is a perspective view of a spring element which functions on the sealing element to cause the sealing action.

In Fig. 1, a standard form of keg is illustrated 10 at 1 having a chime 2 which projects above the surface of a head 3 in the usual manner. The keg has a similar chime 4 at its opposite end.

Positioned in one of the heads, such as the head 3 shown in Fig. 2, is the sealing mechanism, 15 and it preferably is located so that it lies below the level of the chime 2. The structure as shown comprises a bushing 7 secured in an opening in the head, and which securing may be by means of screw-threads as shown. The keg and its 20 head may be of wood or metal, although the trend at the present time is strongly toward the use of metal kegs. The bushing 7 has an opening therethrough in which is secured as by means of screw-threads a second bushing 8. A sleeve of 25 metal or the like, as illustrated at 9, is secured to the inside of the bushing 7 in alignment with the opening through the bushing and therefore in alignment with the second bushing 8.

The bushing 7 has an internal shoulder 11 30 which opposes the end of the bushing 8, and a sealing element is adapted to be clamped between the bushing 8 and the shoulder 11. This sealing element, as illustrated in Fig. 4, has a tubular-like body 12 provided at one end with an outwardly extending flange 13 which may be re-enforced by a metallic insert 14. The tubular body may be pre-formed so that the end opposite the flange 13 is of a gradually flattening arrangement presenting tapered sides 15, as viewed in 40 Fig. 2, while as viewed at right angles thereto as in Fig. 4, the structure appears to be widening. The edges of the seal member come together in contact with each other as two lips 16 and 17 (Fig. 2). This sealing member may be made of 45 rubber or of a synthetic material of a rubber-like nature, or one of the so-called synthetic rubbers, and, of course, the chemical composition is to be such that no objectionable odors or flavors are imparted to the beer.

As shown in Fig. 2 the flange 13 is clamped 50 between the bushing 8 and the shoulder 11. Also, clamped in this position is a spring element as viewed in Fig. 8 having a circumferential flange 20 which may be positioned against the shoulder 11 and spring arms 21 extending downwardly

therefrom and provided with lateral extensions or feet 22. The spring arms extend inwardly as shown in Fig. 2, and the extensions 22 engage the lips 16 and 17 with yielding pressure and urge them against each other to form a sealing contact. As shown in Fig. 3, the tube 9 is slightly elongated in its lower region so as to accommodate the increased length of the seal member 12 when it is collapsed as shown. In this connection, it may be stated that the original form of the sealing member may be such that the lips 16 and 17 are in substantial contact with each other as a normal condition. However, this is not a necessary prerequisite since the spring arms 21 will serve to collapse the member and bring the lips into engagement.

A protecting element in the form of a yielding sleeve is disposed within the rubber sealing member. This protecting member has a tubular body 25 with an annular flange 26 positioned above the flange 13. The lower end of the protecting member is cut to provide a number of fingers 27 which are formed into the position as shown in Fig. 2. The material of which the protecting material is made is such that the fingers may be flexed outwardly as will presently be seen.

For the purpose of providing the auxiliary exterior and interior closures, a post 30 may be journaled in the bushing 7 and provided on the inside of the keg with a closure disc 31 non-rotatably connected to the post and arranged to quite snugly fit over the end of the tube 9. A supporting lug 32 may be provided for engaging the free edge of the closure disc 31. Another closure disc 33 is secured to the post and carried on the top of the bushing 7, and which, preferably, has an enlargement 34 which can be engaged to swing the closure disc 33 to uncover the aperture in the bushing 8. It will be understood that both auxiliary closure discs are non-rotatably secured to the post. A helical spring 35 surrounding the post and located in a recess in the bushing 7 has its opposite ends tied to the bushing and the post respectively, and this spring is arranged to normally hold the discs in closing position as shown in Fig. 2. It is, of course, necessary to also provide a seal around the post, and to this end it may be formed with a tapered portion 40 seating in a tapered seat 41 in the bore through the bushing 7. To maintain this seat a spring 42 backed up by an abutment 43 urges the tapered part 40 against the seat 41.

In Figs. 5, 6 and 7, the arrangement is shown with the so-called "beer tap" applied to the keg. The beer tap may be of conventional construction, and it comprises a fixture or cap 50 with a packing 51 arranged to seat on the bushing 8 and with lugs 52 arranged to be engaged under lugs 53 of the overhanging type on the bushing 8. The under surface of the lugs 53 are inclined as shown (Fig. 5) so that as the fixture 50 is rotated into position, the packing 51 is tightly engaged with the surface of the bushing. The draft tube, commonly called the "tap rod" is illustrated at 55 and it is slidably positioned in the fixture 50 through the means of a packing joint 56.

When the keg is shipped full of its contents the seal and parts thereof are in the position shown in Fig. 2. The lips 16 and 17, which are engaged under the spring pressure of the arms 21, effectively seal the keg to retain the contents therein and to maintain the pressure of the charged liquid. There is no leakage between the bushings,

as a seal is also provided by the parts engaged between the bushing 8 and the shoulder 11. Also, the tapered plug part 40 seals against the tapered seat 41. When the keg is to be tapped the outside sealing disc is turned from the position shown in Fig. 2 to the position shown in Fig. 5, and this also shifts the inner disc out of position. Then the fixture 50 is applied to the bushing 8 and a seal connection is obtained at the packing 51. The draft tube is now pushed downwardly into the barrel and the packing nut 57 is tightened to form a seal at the packing 56. As the draft tube is pushed downwardly, its end first engages the tapering fingers 27 and expands the same and therefore expands the tapered walls 15 of the rubber sealing element. Thus the rubber sealing element is protected from being marred or cut by the end of the draft tube. When the draft tube is in position the rubber sealing element need not necessarily engage the same around its entire periphery, as shown in Fig. 6, since a seal is effected at 51 and at 56. When the draft tube is withdrawn the parts return to the position shown in Fig. 2 with the lips 16 and 17 coming together to close the opening and to thus keep out all dirt and vermin. The spring 35 causes a closure of the auxiliary closing discs so that exterior dirt and vermin have no access to the interior of the rubber sealing element. When it becomes necessary to remove the lining from the interior of the keg heat is applied to melt the pitch, and the lips 16 and 17, and in fact the entire rubber sealing element, are protected. When a new pitch lining is applied, it is applied to the interior disc as well as to other exposed parts, but not to the lips 16 and 17, as these are protected.

I claim:

1. A seal structure for the draft opening of a keg for a beverage such as beer comprising, a bushing adapted to be located in the wall of the keg, a tubular sealing member of rubber or rubber-like material positioned in alignment with the bushing and having an end adapted to be located within the keg, yielding means for holding said end of the tubular member collapsed to close and seal the passage through the tubular member and bushing and adapted to be spread when a draft tube is forced through the bushing and tubular member, a guard carried by the bushing and extending inwardly of the keg and surrounding said projecting end of the tubular member, a closure cap movable to and from a position for closing the inner end of the guard, another closure cap for covering the bushing on the exterior of the keg, and common means upon which the caps are mounted so that the caps may be shifted simultaneously to and from closed position.

2. A seal structure for the draft opening of a keg for a beverage such as beer comprising, a bushing adapted to be located in the wall of the keg, a tubular sealing member of rubber or rubber-like material positioned in alignment with the bushing and having an end adapted to be located within the keg, yielding means for holding said end of the tubular member collapsed to close and seal the passage through the tubular member and bushing and adapted to be spread when a draft tube is forced through the bushing and tubular member, a tubular guard extending inwardly from the bushing and surrounding said projecting end of the tubular member, a closure cap movable to and from a position for closing the inner end of the guard, another closure cap for covering the bushing on the exterior of the

keg, and common means rotatably positioned in the wall of the keg adjacent the bushing and to which the caps are secured and which is operable to swing the caps to and from closing positions.

3. A seal structure for the draft opening of a keg for a beverage such as beer comprising, a bushing adapted to be located in the wall of the keg, a tubular sealing member of rubber or rubber-like material positioned in alignment with the bushing and having an end adapted to be located within the keg, yielding means for holding said end of the tubular member collapsed to close and seal the passage through the tubular member and bushing and adapted to be spread when a draft tube is forced through the bushing and tubular member, a tubular guard supported by the bushing and surrounding said projecting end of the tubular member, a closure cap movable to and from a position for closing the end of the guard, another closure cap for covering the bushing on the exterior of the keg, common means rotatably positioned in the wall of the keg adjacent the bushing and to which the caps are secured and which is operable to swing the caps to and from closing positions, and spring means acting upon the common means to normally hold the caps in the position for closing the opening of the bushing on the exterior of the keg and for closing the opening of the tubular guard on the interior of the keg.

4. A seal structure for the draft opening of a keg for a beverage such as beer comprising, a bushing adapted to be located in the wall of the keg, a tubular sealing member of rubber or rubber-like material positioned in alignment with the bushing and having an end adapted to be located within the keg, yielding means for holding said end of the tubular member collapsed to close and seal the passage through the tubular member and bushing and adapted to be spread when a draft tube is forced through the bushing and tubular member, a tubular guard surrounding said projecting end of the tubular member, a closure cap movable to and from a position for closing the open end of the guard, another closure cap for covering the opening in the bushing on the exterior of the keg, common means rotatably positioned in the wall of the keg adjacent the bushing and to which the caps are secured and which is operable to swing the caps to and from closing positions, spring means acting upon the common means to normally hold the caps in the position for closing the opening of the bushing on the exterior of the keg and for closing the opening of the tubular guard on the interior of the keg, and means forming a rotatable and sealed joint between the wall of the keg and said rotatable member.

5. In a keg for a beverage such as beer, a seal structure for the draft opening comprising a member secured in the keg wall and having an opening therethrough, a bushing in the opening, a tubular member held in position between the bushing and the member and projecting inside the keg, guard means inside the keg surrounding the projecting end of the tubular member, yielding means for collapsing the inner end of the tubular member to close and seal the passage through the bushing and through the tubular member and adapted to yield when a draft tube is inserted therein, and closure caps shiftable to and from closing position for covering the open-

ing in the bushing on the exterior of the keg and the opening of the tubular guard on the interior of the keg.

6. In a keg for a beverage such as beer, a seal structure for the draft opening comprising a member secured in the keg wall and having an opening therethrough, a bushing in the opening, a tubular member held in position between the bushing and the member and projecting inside the keg, guard means inside the keg surrounding the projecting end of the tubular member, yielding means for collapsing the inner end of the tubular member to close and seal the passage through the bushing and through the tubular member and adapted to yield when a draft tube is inserted therein, closure caps shiftable to and from closing position for covering the opening in the bushing on the exterior of the keg and the opening of the tubular guard on the interior of the keg, and means within the tubular member adapted to be engaged by and expanded by the draft tube as the same is projected through the tubular member to protect the tubular member from the end of the draft tube.

7. A seal structure for the draft tube opening of a keg for a beverage such as beer comprising, a bushing adapted to be secured in the wall of the keg, and having a shoulder in its opening, a second bushing secured in the opening of the first bushing, a tubular member of rubber or rubber-like material having a flange at one end engaged between the second named bushing and the shoulder of the first bushing and adapted to project into the keg, a guard surrounding the projecting end of the tubular member, yielding means for collapsing the projecting end of the tubular member to close and seal the passage through the second bushing and tubular member and adapted to yield and expand when a draft tube is forced through the tubular member, a post rotatably mounted in the first bushing and having a sealed connection therewith, and two caps secured to the post and shiftable upon rotation around the post as an axis to and from positions for closing the exterior opening in the second named bushing and the opening in the guard.

8. A seal structure for the draft opening of a keg for a beverage such as beer comprising, a bushing adapted to be located in the wall of the keg, a tubular sealing member of rubber or rubber-like material positioned in alignment with the bushing and having an end adapted to be located within the keg, yielding means for holding said end of the tubular member collapsed to close and seal the passage through the tubular member and bushing and adapted to be spread when a draft tube is forced through the bushing and tubular member, means within the tubular member comprising relatively collapsible fingers for protecting the inner surfaces of the tubular member upon insertion of a draft tube, a guard surrounding the tubular member, said guard being carried by the bushing and extending inwardly of the keg to an extent at least equal to the inward extent of the tubular member, and a closure cap pivotally mounted in the bushing on an axis substantially paralleling the axis of the tubular member and swingable to and from a position closing the inner end of the guard.

T. N. BOURKE.
